UNITED STATES PATENT OFFICE.

HENRY C. BUSH, OF PERCILLA, TEXAS.

WASHBOARD.

1,105,124.

Specification of Letters Patent. Patented July 23, 1914.

Application filed July 2, 1913. Serial No. 777,073.

To all whom it may concern:

Be it known that I, HENRY C. BUSH, a citizen of the United States, residing at Percilla, in the county of Houston and State of Texas, have invented a new and useful Wash-board, of which the following is a specification.

The present invention appertains to wash boards, and aims to provide a novel and improved device of that character.

It is the object of the present invention to provide a wash board of simple durability, and cheap construction, which shall also be serviceable and efficient in its use.

With the foregoing general objects outlined, and with other objects in view, which will be apparent, the invention resides in the combination and arrangement of parts and in the details of construction hereinabove described and claimed, it being understood that changes in the precise embodiment of the invention herein disclosed can be made within the scope of what is claimed without departing from the spirit of the invention.

The invention has been illustrated in its preferred embodiment, in the accompanying drawings, wherein—

Figure 1 is a perspective view of the improved wash board. Fig. 2 is a cross section thereof, taken on the line 2—2 of Fig. 1.

In carrying out the invention, there is employed, the usual base or back board 1, which may be secured between the legs 2, or which may be secured to any other suitable frame. The base board 1 provides a smooth rubbing surface upon which are secured, in a novel manner, a plurality of series of longitudinal and transverse wires to effect a thorough cleansing action.

A plurality or series of equi-distant longitudinal wire strands 3 are secured upon the rubbing surface of the base board 1, and have their ends clenched through the board adjoining the upper and lower ends thereof. Two series of transverse wire strands 4 are secured upon the rubbing surface of the board 1 adjoining the respective sides, the ends of the strands 4 being clenched through the board over the outermost or remote strands 3 and over those strands 3 adjoining the central longitudinal strand. There is also employed a central series of transverse wire strands 5, which are disposed be-

tween the respective strands 4, and which have their ends projecting between the respective aforesaid strands 4 and clenched through the board 1 over the longitudinal strands 3 adjoining the outermost or remote longitudinal strands. The respective transverse strands are thus in staggered relation with respect to one another, the end portions of the central series of strands 5 extending between the respective series of side strands 4.

The transverse strands being secured over the longitudinal strands will be spaced from the rubbing surface, which will provide a more effective cleansing action, when the clothes are rubbed over the board as usual. The transverse strands being secured over the longitudinal strands, as described, will also reduce the liability of the clothes being torn or injured, and furthermore, the transverse strands being spaced from the rubbing surface will permit the wash water to readily run down the rubbing surface underneath the transverse strands and between the respective longitudinal strands. The longitudinal strands are also locked underneath the transverse strands in order that they may not become dislodged, and in order to prevent them from being sprung sidewise.

The present wash board may be inexpensively manufactured, the same being simple and durable in construction.

Having thus described the invention, what is claimed as new is:

A wash board including a back board, a series of longitudinal wires laid thereon and having their terminals clenched therethrough, two longitudinal series of relatively short side transverse wires laid upon the longitudinal wires, the said transverse wires being spaced from the central longitudinal wire, the outer extremities of the said transverse wires being bent over the side longitudinal strands and clenched through the back board, the inner ends of the said transverse wires being bent over certain of the longitudinal wires between the central and side longitudinal wires and being clenched through the back board, and a longitudinal series of relatively long central transverse wires laid upon the longitudinal wires between the side transverse wires, the ends of the central transverse wires projecting between the ends of the respective side transverse wires and being bent over those longi-

itudinal wires between the ends of the side transverse wires and clenched through the back board, whereby the transverse wires will have double spaced portions at the side and central points, and will have single portions intermediate the said double spaced portions.

In testimony that I claim the foregoing as my own, I have hereto affixed my signature in the presence of two witnesses.

HENRY C. BUSH.
